UNITED STATES PATENT OFFICE.

HANS OTTO SWOBODA, OF EAST ORANGE, NEW JERSEY.

PANEL-BOARD.

SPECIFICATION forming part of Letters Patent No. 752,125, dated February 16, 1904.

Application filed December 22, 1902. Serial No. 136,123. (No model.)

To all whom it may concern:

Be it known that I, HANS OTTO SWOBODA, a citizen of the United States, residing at East Orange, county of Essex, State of New Jersey, 5 have invented certain new and useful Improvements in Panel-Boards, of which the following is a specification.

My invention relates to panel-boards of the type used for connecting conductors of a number of distributing-circuits through fuses or switches to the bus-bars of an electric distribution-circuit.

My invention consists in various details of construction of the panel-board, which will 15 be set forth in the specification.

The object of my invention is to simplify and cheapen the construction of panel-boards, and this I accomplish by making the panel-boards of a definite size, arranging the bus-bars parallel and in such manner that two of such bars shall be located near to the outer edges of the panel-board, and locating the fuses and switches and other connecting devices between the bus-bars.

25 The accompanying drawings will serve to illustrate my invention.

Figure 1 is a front view of a panel-board, showing an arrangement of bus-bars and fuses. Fig. 2 is a transverse section of Fig. 1 on line 30 $\alpha \alpha$. Fig. 3 is a front view of a panel-board with bus-bars, fuses, and switches. Fig. 4 is a transverse section of Fig. 3 on line $\gamma \gamma$.

Similar numerals indicate like parts.

In the drawings, 5 represents the supporting-base for the panel-board, which may be of any suitable shape or material. Preferably I give to the base definite dimensions in order that it may be used in connection with the various devices commonly employed in 40 connection with the separate distributing-conductors of a distribution-circuit—such, for instance, as fuses, switches, motor connections, and the like.

Mounted upon the face of the board and 45 near to its outer edges are the bus-bars 6 6^a. In Fig. 3 the panel-board is shown as arranged for a three-wire circuit with three bus-bars, two of which, 6 6^a, are located near to the outer edges of the board and one, 6^b, at the 50 center of the board. If the panel-board is to

be provided with more than three bus-bars, such bus-bars will be disposed parallel and equally distant on the face of the board. Two bus-bars, however, will always be located near to the outer edges of the board. 55

Situated between the bus-bars 6 6^a of Fig. 1 or 6 6^b 6^a 6^b of Fig. 3 are the blocks 7. These blocks may be of any suitable construction and have terminal screws 8 and 9. Terminal screw 8 is connected through fuse 10 60 with bus-bars 6 6^a, Fig. 1, and 6, 6^a, and 6^b, Fig. 3. Connected to the terminal screws 9 are the conductors 11 12 for the distributing-circuits. As shown in Fig. 1, these conductors are carried through openings 13, situated 65 between the blocks 7.

In the construction shown in Fig. 3 there are used in connection with the blocks 7 the switches 14. These switches may be of any suitable type, but preferably provided with 70 the two switch-blades 15 16, connected through the non-conducting handle 17. These switches are connected in circuit as follows: bus-bar 6 or 6^a, fuse 10, terminal screw 8, with its block 7, post 18, forming a part of it, switch-blade 75 15, pivoted to the post, contact 19, forming part of another block 7, with the terminal screw 9 to the distributing-conductor 11. Bus-bar 6^b is connected through fuse 10, terminal screw 8, with its block 7, contact 20, switch-blade 16, pivoted to post 21, forming part of another block 7, with the terminal screw 9 to the distributing-conductor 12. 80

The conductors 11 12 for the distributing-circuits are carried separately through openings 22 23, formed through the body of the 85 panel-board.

It will be observed from the construction shown in Fig. 3 that when a switch 14 is closed the distributing-conductors 11 are cut into circuit with the bus-bars 6 or 6^a, depending upon 90 the positions of the switch, and the distributing-conductors 12 cut into circuit with the bus-bar 6^b.

Having thus described my invention, I 95 claim—

1. In a panel-board, the combination of a supporting-base, bus-bars mounted thereon, switches arranged on the supporting-base between said bus-bars, said switches consisting 100

of two switch-blades connected but insulated from each other, and two contacts, and said switches connected through one blade to one bus-bar and through one contact to the opposite bus-bar.

2. In a panel-board, the combination of a supporting-base, bus-bars thereon, distributing-conductors leading therefrom, switches arranged on said supporting-base between said bus-bars, said switches consisting of two switch-blades, and two contacts, said switches connected through one blade to one bus-bar, and through the opposite blade to one distributing-conductor, and through one contact to the opposite distributing-conductor, and through the opposite contact to the opposite bus-bar.

3. In a panel-board, the combination of parallel bus-bars, distributing-conductors, and switches interposed between said bus-bars and arranged on said panel-board, said switches composed of two pivoted contact-blades and two contact-clips insulated from each other, the connection being such that a contact-blade and its coacting contact-clip are respectively connected to one bus-bar and one distributing-conductor.

4. In a distribution panel-board, the combination with bus-bars secured to said panel-board, of a double-pivoted knife-switch, and contacts for engagement thereby secured on

the panel-board between the bus-bars, an electrical connection between one switch-blade terminal and the adjacent bus-bar and between one contact and the bus-bar adjacent thereto, and distributing-conductors connected to the other switch-blade and to the other contact, respectively, whereby the terminals of the distributing-conductors are, respectively, far removed from the bus-bar to which they are electrically connected.

5. In a distribution panel-board, the combination with bus-bars secured to said panel-board, of a double-pivoted knife-switch, and contacts for engagement thereby secured on the panel-board between the bus-bars, a fuse connection between one switch-blade terminal and the adjacent bus-bar and between one contact and the bus-bar adjacent thereto, and distributing-conductors connected to the other switch-blade and to the other contact, respectively, whereby the terminals of the distributing-conductors are, respectively, far removed from the bus-bar to which they are electrically connected.

In testimony whereof I affix my signature in the presence of two witnesses.

HANS OTTO SWOBODA.
